SETTING MEANS FOR ENDLESS TYPE
MEMBERS

Herman I. Lippard, Lake Worth, Fla.

Application September 3, 1947, Serial No. 771,976

6 Claims. (Cl. 101—111)

1

The invention relates to tag or ticket printing devices, and is in the nature of an improvement on the tag printing device disclosed in my prior Patent No. 2,103,752 issued December 28, 1937. This application is a continuation-in-part of application Serial No. 511,674 filed November 25, 1943, now abandoned.

Briefly stated, the device of my prior patent consists essentially of a base upon which one or more type-carrying frames are mounted for reciprocation toward and away from the printing surface. These frames are of substantially flat form disposed with their planes substantially perpendicular to the printing surface, and carry a line of changeable characters on their lower ends, said line of characters constituting the printing type. Each character is one of a number of characters carried by a strip of flexible material mounted in a suitable manner on each of the frames, the characters being changeable by moving the flexible strips. The frames are pivoted about a horizontal axis perpendicular to their planes so that they may be swung away from the base to facilitate changing of the type.

The present invention is directed particularly to means for facilitating changing the type, i. e. type-setting. In order clearly to disclose the invention without unnecessary details, the invention will be illustrated in the form of a simplified device having a single type-carrying frame.

Referring briefly to the accompanying drawings:

Figure 1 is a front elevation of a preferred and illustrative embodiment of the invention, part being broken away;

Figure 2 is a plan view;

Figure 3 is a view taken on line 3—3 of Figure 1, part being broken away;

Figure 4 is a detail of a type-carrying frame, with parts broken away to reveal internal construction;

Figure 5 is a perspective view showing the relationship of the type-carrying frame and the means for swinging the frame to and away from the base;

Figure 6 is a front elevation of an alternate embodiment of the invention;

Figure 7 is a side elevation of the embodiment of Figure 6 with portions broken away, and

Figure 8 is a sectional view along the line 8—8 of Figure 6.

Referring to the drawings in greater detail, the letter T designates a table top or other suitable support for the device. The tag or ticket

2

to be printed upon may be of any conventional form and need not be described.

The base portion of the device is denoted generally by the numeral 1, and is shown as having the general form of an inverted U, the legs of which are indicated by 2 and 3, and the yoke portion by 4. Secured to the yoke portion 4 is a cylindrical tubing 5, through which extends a reciprocatable plunger 6. Telescopically mounted on the tubing 5 is a cylindrical casing 7, which serves as a handle to reciprocate the plunger 6. Suitable means (not shown) may be provided to maintain the plunger 6 normally in its uppermost position, and to return the handle to said position when pressure on the handle 7 is removed.

The numeral 8 denotes a vertical plate mounted on the front of the base 1 so as to move up and down with the plunger 6 when the handle 7 is reciprocated. Mounted between the legs 2 and 3 of the base 1 is an inking pad P of suitable form, which is normally maintained with its upper or inking surface against the face of the type on the lower end of the type-carrying frame, and which is so mounted so as to swing out of the way of the type-carrying frame as the frame is moved toward the tag or ticket. The connections between the reciprocating plunger 6 and the vertical plate 8 and between said plunger and the inking pad do not constitute parts of this invention, and hence are not shown. Reference is hereby made to Figure 2 of Patent No. 2,103,752, wherein is illustrated a suitable form of mounting for the inking pad. The vertical plate 8 may be connected to the reciprocatable plunger 6 in substantially the same manner as the housing 2 in Figure 2 of said drawing is connected to the reciprocatable plunger 101.

Hingedly connected to the plate 8 at 9 is a second vertical plate 10, which is adapted to be swung about the hinge 9 into and out of contact with the plate 8. The normal position of the plate 10 is against the plate 8, the pivotal movement rendering it possible to swing the printing plates and the associated structure horizontally away from the base, whenever it is desired, as for instance when repairs are to be made. The plate 10 may be secured in normally closed position with reference to plate 8 by means of a latch 11, pivotally secured to the plate 8.

The end of plate 10 opposite hinge 9 is bent forward to form a projecting arm 12. Secured to said arm are two closely spaced vertical plates 13 and 14. The numeral 15 denotes the type-

carrying frame shown in detail in Figure 4. This frame has a projecting ear 16 (see Figure 5), by means of which it is pivotally mounted between plates 13 and 14 on a bushing 17. The bushing 17 is provided with the diametrically opposite slots 18 for a purpose to be described.

As will hereinafter be described, the frame 15 is adapted to be swung from position A in Figure 1 (solid lines) about the ear 16 to position B (dotted lines). The frame 15 is normally locked in position A by means of a latch member 19. This latch member is pivotally supported between the plates 13 and 14, and has a hook at one end extended to engage a pin 21 on frame 15. The opposite end 22 of the latch member projects to the right for a purpose which will appear later. A spring 23 urges the latch member in a counter-clockwise direction so as to lock the frame 15 in position A.

Reference numerals 24 and 25 denote two horizontal track members secured to the outer side of the projecting arm 12 in parallel vertical relationship, and provided with opposing slots 26 and 27. Secured to the outer side of the arm 12 midway between the members 24 and 25 is a gear rack 28. A carriage denoted by the numeral 30 is slidably mounted on the track members 24 and 25 by means of the vertical plate 31, which is received in the slots 26 and 27.

Secured to the vertical plate 31 of the carriage 30 is an L-shaped bracket 32, the vertical leg being denoted by 32' and the horizontal leg by 32''. Rotatably mounted on the upper end of the vertical leg 32' is a key 33 having the diametrically opposite projections 34, and being in axial alinement with the bushing 17. The projections 34 of the key 33 are adapted to be engaged with the slots 18, and when so engaged the type frame can be turned about the ear 16 to the position B by rotation of the key 33. The outer or free end of the key may be provided as shown with an operating knob 35 for easy manipulation.

Reference numeral 36 designates a narrow rod rotatably mounted parallel to the key 33 in the carriage 30 in a suitable manner, and provided at its outer end with an operating handle 37. Fixedly secured to said rod is a cam 38, provided on one side with a projecting ear 39. Said ear is adapted to engage between the plates 13 and 14, when alined therewith and rotated counter-clockwise by means of the handle 37.

The reference numeral 40 denotes a vertical rod slidably mounted through the horizontal leg 32'' of the bracket 32 below the cam 38. The rod is urged upwardly against the cam by means of a spring 41. When the rod 36 is rotated counter-clockwise, the high side of the cam is brought into contact with the rod 41, urging it downwardly against the pressure of the spring 41. When the projecting ear of the cam 38 is alined between the plates 13 and 14, the rod 40 is directly above the end 22 of latch member 19. Hence, counter-clock rotation of the rod 36 serves to lock the carriage 30 with its attendant mechanism against relative movement with respect to the type-carrying frame 15, and unlocks the latch member which normally holds said frame against turning movement. This last action is accomplished when rod 40, being pressed down by cam 38, depresses the free end 22 of latch member 19, thereby turning the latch member and disengaging the hook 19 from pin 21 on plate 15. At this described position of the carriage 30, the bracket 32 is so located as to bring

the projections 34 of the key 33 into engagement with slots 18 of bushing 17. Hence, by turning the knob 35 clockwise, the type frame 15 is turned to position B shown in Figure 1.

5 The numerals 45 and 46 respectively denote a narrow tube and a rod which extend in horizontally spaced relation from the carriage 30. Mounted for slidable movement on the tube 45 and rod 46 is a U-shaped member 47. The U-shaped member may advantageously be provided with a tubular bushing 48 to receive the rod 46, thereby providing greater rigidity. Notches 49 may be provided on the tube 45, and a spring 50 may be secured to the U-shaped member so as 10 to engage in any selected notch, thereby securing the U-shaped member in a desired position 15 against accidental displacement.

A shaft 51 extends through the tube 45. The outer end of the shaft is provided with a knob 20 52, and the inner end thereof is provided with a gear 53, which meshes with the gear rack 28 on the arm 12. It will be understood that the entire carriage 30 can be moved horizontally on the track members 24 and 25 by simply turning 25 the knob 52. It will also be understood that when the projecting ear 39 of cam 38 is in engagement with the vertical plates 13 and 14, the type frame 15 is in alinement with the space between the legs 55 and 56 of the U-shaped member 47, and can be turned by means of knob 35 to position 30 B of Figure 1 between said legs.

Slidably mounted on each of the legs 55 and 56 is a sleeve or finger piece 57. They are each 35 constructed of a narrow U-shaped piece of metal 60, closed off by a serrated strip 61 riveted or brazed in place, and are provided with a flat friction spring 62 riveted inside the member 60 at the bottom of the U. These springs hold the sleeves or finger pieces on the legs wherever they 40 are placed.

The U-shaped member 47 and the slidable sleeves or finger pieces 57 constitute mechanical means for setting the type on the type-carrying frame 15.

45 The construction of the type-carrying frame is shown in detail in Figure 4. This frame is constructed of two thin rectangular plates 65 and 66 separated by spacers 67. The ear 16 previously referred to is secured between the plates 65 and 66 above the horizontal center line, and projects to one side as shown. The frame 15 is provided as shown in Figure 1 and at the lower part of Figure 4 with a number of parallel closely spaced type-bands L, which extend vertically about both flat faces of the frame and over the upper and lower ends. As many type-bands as necessary within the width of the frame may be used. The type-bands are preferably of an elastic material such as rubber and carry all the 60 characters necessary for a particular purpose, as for instance, the printing of price tags in a department store.

As shown in Figures 1 and 4, the type-carrying frame is provided with means to hold the type-bands taut about the frame while permitting each 65 of the bands to be selectively shifted to bring any desired character into printing position. These means preferably consist of a plurality of rods 68 mounted vertically between the plates 65 and 66, and extending above the upper edge thereof. There are as many rods as lines of type. The rods 68 terminate at the upper ends in bearing blocks 69 provided with lipped sides 70 to retain the type-bands L. The rods have a 70 rectangular upper portion 71 and a circular lower 75 portion 72.

portion 72, terminating in a hook 73. Guide pins 74 are provided between the plates 65 and 66 on each side of each rod. A horizontal plate 75 spans the space between the plates 65 and 66 at the top of the type-carrying frame 15, and is provided with apertures 76 to receive the rods 68. The rods are pressed upwardly by springs 77 coiled about the circular lower portions 72. The pins 74 and the apertures 76 guide the rods in their vertical movement. Rotation of the rods is prevented by the fact that both they and the apertures 76 are rectangular. Contact of the hooked lower ends of the rods with the guide pins 74 limits the upward movement of the rods.

It is to be noted that the rods 68 do not all extend the same amount above the upper edge of the frame 15. They preferably alternate in the amount of extension, every other one extending the same amount. Hence, it is possible to overlap the bearing blocks 69 and thereby bring the rods 68 closer together, so that the endless type-bands are in substantial contact.

When the type frame 15 is in position A, the bottom thereof presents a changeable line of type, each character thereof constituting an element of one of the type-bands L. This line of type can be brought down against a tag or ticket positioned on the support T so as to print a line of characters (letters and/or numerals) thereon by reciprocating the plunger 1. Ink is provided by the inking pad P, which, as previously stated, is normally maintained with its inking surface against the face of the type, and which is mounted so as to swing out of the way of the type frame as the frame is moved toward the support T.

When the type frame is in position B, it is inverted so that the line of printing type is in full clear view, thereby greatly simplifying the task of type-setting. This can be done by manipulating each of the type-bands L by means of the fingers until a desired line of characters is presented on the upper or printing edge. The preferred way of setting or changing the type is by means of the U-shaped member 47 and the slideable sleeves or finger pieces 57.

The manner of setting or changing the type by means of the U-shaped member 47 and the slideable sleeves can be readily understood by reference to Figures 1 and 5. When the type frame 15 is in type-setting position indicated by dotted lines (position B), it is straddled by U-shaped member 47. This member may be shifted horizontally along the tube 45 and the rod 46 into alinement with any desired type-band L. The type-band can then be moved to bring a desired character to the printing edge by pressing the sleeves or finger pieces 57 against the type-frame and moving one of them upwardly and the other downwardly at the same time. The serrated surfaces 61 serve to move the type-band L against the pressure of the springs 77 (Figure 4). In actual operation, it has been found that two sleeves or finger pieces are essential, in order to provide the push-pull action, which is necessary to shift the type-bands. The U-shaped member can be moved from one type-band to the next, as one type-band after the other is shifted to bring a desired character into printing position, i. e. on the printing edge of the frame.

It is to be understood that while only one type frame is illustrated, a plurality of them can be mounted on plates similar to 13 and 14 along the projecting arm 12. The U-shaped member 47 can then be moved from one frame to another by rotating the knob 52 to move the carriage 30

to the desired frame, locking the carriage in such position by rotating the handle 37, and simultaneously unlocking the attendant latch 18 of the desired frame. The projections 34 of key 33 can then be engaged with the slotted bushing 17 of the desired frame, and the desired frame turned to position B between legs of yoke 47 by rotating the handle 35.

An alternative form of device embodying the type-setting mechanism of the invention is shown in Figures 6, 7 and 8. This device is illustrated as being a single line hand type printer, and comprises an inverted U-shaped frame 100 formed of a strip of flat metal. The horizontal portion of the U is denoted by 101 and the two legs by 102 and 103. A handle (not shown) may be fitted to portion 101 if desired. At the extremities of the legs 102 and 103 are retaining springs 104 to secure the type frame, which is noted by 15', in position. This frame may advantageously be of the same structure as the corresponding frame 15 in the first embodiment, and is provided with exactly similar parallel closely spaced type-bands L. The inside surfaces of legs 102 and 103 are provided with grooves 105 and 106 respectively. Said grooves are adapted to receive the type frame 15', and terminate at points 107 and 108, respectively, so determined as to leave the printing surface 109 of type frame projecting below the legs 102 and 103. A space indicated by 110, is also provided above the type frame.

The reference numerals 112 and 113 designate two cross-bars parallel to the plane of the type-carrying frame 15'. These cross-bars are supported, one on each side of the device, by tabs or projections denoted by 111, which are secured to the legs 102 and 103 somewhat below the horizontal portion 101 of the U-shaped frame. Securing means such as nuts 114 fasten these cross-bars rigidly in place. The cross-bar 112 is provided with notches 115 cut at regularly spaced intervals along its uppermost side for a purpose to be hereinafter pointed out.

A yoke 116 is mounted on the cross-bars 112 and 113 with its plane perpendicular to the plane of the U-shaped frame 100 by means of the bearing blocks 117 and 118 for slideable movement in a direction parallel to the type frame 15'. Bearing block 117 is provided with a spring 119, secured thereto as at 120, which spring is adapted to engage in any one of the notches 115 in the cross-bar 112. The location and spacing of these notches are such as to cause the bearing blocks to be alined with any desired type-band carried by the type frame 15'.

At this point, it is to be noted that yoke 116 is an inverted U-shaped element having its closed or round end 121 passing through the space 110 between the U-shaped frame 100 and the type frame 15', and that the legs 122 of the yoke extend downwardly over the front and back faces of the type frame 15' and through the supporting bearing blocks 117 and 118. Because of the described structure, the yoke 116 may be brought into alinement with any particular type-band, when it is desired to shift said band so as to bring a particular character to the printing surface 109 of the type frame 15'.

Slidably mounted on the legs 122 of the yoke 116 are two identical sleeves or finger pieces 57', which are substantially identical with the sleeves 57 previously described with reference to the first embodiment. They are each constructed of a narrow U-shaped member 60' closed off by a serrated strip 61' suitably secured in place, and

are provided with a flat friction spring 62' riveted inside the member 60' at the bottom of the U. These springs 62' serve to hold the sleeves or finger pieces on the legs wherever they are placed.

The type bands L' may be shifted in the following manner: The yoke 116 is first positioned in alinement with the type-band to be changed, by sliding the bearing blocks 117 and 118 over the rods 112 and 113 respectively to the desired position. The spring 119 is lifted clear of the notches 115 during the moving operation, and permitted to engage with the notch 115 which centers the said yoke in alinement with the desired type-band. Then by urging the spring held sleeves 57' inward against the pressure of springs 62', the serrations of elements 61' are caused to engage with the type-band to be moved. One of the sleeves or finger holds 57' is then moved upwardly and the opposite one is moved downwardly, until the desired character on the type-band L' is brought to the printing surface 109 of the device.

It will be understood in conclusion that the foregoing disclosure is illustrative and not restrictive of the invention.

I claim:

1. In a tag printing device, the combination of a base, a frame of flat form mounted on said base with its plane substantially perpendicular to the printing surface, a series of spaced endless bands passing about both flat faces of the frame and over both ends, a series of characters carried by each of the endless bands, the line of characters on one end of the frame constituting the printing type, means for mounting said frame so that it may be swung to and away from the printing surface, and means associated with said base and operative when the frame is swung away from the printing surface to move the endless bands so as to present a desired line of characters on the printing end of the frame, said last mentioned means consisting of a U-shaped element to receive the frame between its arms when said frame is swung away from the printing surface, and means carried by each of said arms and adapted to contact and to shift a selected endless band on said frame to bring a desired character into printing position on the printing end of the frame.

2. In a tag printing device, the combination of a base, a frame of flat form mounted on said base with its plane substantially perpendicular to the printing surface, a series of spaced endless bands passing about both flat faces of the frame and over both ends, a series of characters carried by each of the endless bands, the line of characters on one end of the frame constituting the printing type, means for mounting the frame so that it may be swung to and away from the printing surface, and means operative when the frame is swung away from the printing surface to move the endless bands so as to present a desired line of characters on the printing end of the frame, said last mentioned means consisting of a U-shaped element to receive the frame between its arms when the frame is swung away from its perpendicular relationship, and a finger piece slidably mounted on each of the arms of said element, said finger pieces being adapted to contact and to shift a selected endless band on said frame to bring a desired character into printing position on the printing end of the frame.

3. A type-carrying frame consisting of a hollowed plate member of substantially flat form, a plurality of rods extending from one end of said

plate member, spring means within the hollowed portion of said plate member urging said rods away from the end of said plate member, a bearing member secured to the outer end of each of said rods, a series of spaced endless bands, each of said bands passing about both flat faces of said plate member, over one of said bearing members and over the end of said plate member opposite said bearing members, a series of characters carried by each of said bands, the line of characters on the end of said plate member opposite the bearing members constituting the printing type, said spring means serving to hold said bands taut.

15 4. The type-carrying frame defined in claim 3, the adjacent rods extending different amounts beyond the end of said frame, thereby enabling the endless bands to be positioned closely together.

20 5. A device for setting an endless type member, said device comprising a pair of parallel arms adapted to receive the type member between them, a finger piece slidably mounted on each of said arms, spring means between each of said

25 finger pieces and its supporting arm to hold said finger pieces out of contact with opposite portions of said type member and to permit said finger pieces to be brought manually into contact with said type member, said finger pieces when brought into contact with said type member being adapted conjointly to shift said type member, thereby bringing a desired character into printing position.

30 6. In a tag printing device, wherein the lines 35 of type are in the form of endless bands carried by a flat frame, means for moving the endless bands so as to present a desired line of printing characters, said means comprising a pair of connected parallel arms adapted to receive said

40 frame between them, said arms being mounted on said device for slidable movement transversely of said bands and being adapted to be positioned in juxtaposition to a selected band, a finger piece slidably mounted on each of said arms, spring

45 means between each of said finger pieces and its supporting arm to hold said finger pieces out of contact with opposite portions of the juxtaposed band and to permit said finger pieces to be brought manually into contact with the opposite 50 portions of the juxtaposed band, said finger pieces when brought into contact with the juxtaposed band being adapted conjointly to shift said band, thereby bringing a desired character into printing position.
